UNITED STATES PATENT OFFICE.

EINAR A. TANNAS, OF AMBROSE, NORTH DAKOTA.

SELF-FEEDING CONTAINER.

1,313,613.

Specification of Letters Patent. Patented Aug. 19, 1919.

Application filed May 10, 1919. Serial No. 296,207.

To all whom it may concern:

Be it known that I, EINAR A. TANNAS, a citizen of the United States, residing at Ambrose, in the county of Divide and State of North Dakota, have invented certain new and useful Improvements in Self-Feeding Containers, of which the following is a specification, reference being had to the accompanying drawings.

This invention relates to containers for holding granular materials, and particularly to a container so constructed that it will hold a certain quantity of the material and discharge it little by little upon the feed trough or bottom of the device as required.

A further object is to provide a device of this character which is particularly adapted for use in open fields and which will act to protect the material being fed from the container and prevent it from being scattered over the field, being washed away by rain, or covered with mud.

A further object is to provide a device of this character made of metal and so designed that the cover is locked in place from accidental opening and the container is held to the ground by single anchoring means.

A further object is to provide a device of this character having such details of construction that the container may be cheaply formed and put together without the use of solder by simply slipping the parts into engagement with each other.

My invention is illustrated in the accompanying drawings, wherein:

Figure 1 is a perspective view of a container constructed in accordance with my invention;

Fig. 2 is a perspective view of one member 15;

Fig. 3 is a vertical transverse section of the trap; and

Fig. 4 is a section on the line 4-4 of Fig. 3.

Referring to these drawings, it will be seen that my container is oblong in form and consists of a bottom 10 and integral side walls 11. The sides are formed with end flanges 12 and the bottom with an end flange 13. These flanges 13 are bent over tightly upon themselves, but the flanges 12, as illustrated in Fig. 4, are bent back upon themselves, as at 14, to provide a vertically extending groove on each side wall. The front and rear walls 55 are designated 15 and are identical in form. Each wall, as illustrated in Fig. 2, is formed

of two plates or sheets of metal, one of these plates 16 having inwardly turned flanges 17 on its side margins, these flanges extending downward from the top of the plate a predetermined distance. Below these flanges, the plate is angularly bent, as at 18. Sliding within the bent margins 17 of the plate 16 is a plate 19, the upper end of which is angularly flanged, as at 20, the lower portion of the plate being angularly bent, as at 21, and disposed in divergent relation to the bent portion 18 of the plate 16, and the plate is notched, as at 22, at this bend to accommodate the flanges 12 of the side walls.

The compound wall 15, constructed as above described, is designed to be slipped into place between the side walls, the inwardly turned margins 17 engaging within the inwardly turned margins 14 of flanges 12 in the manner illustrated in Fig. 4. The walls 15 are slipped downward into place, with the angular portions or water-sheds 19 projecting outward and the angular portions 18 projecting inward until the flange 20 strikes the upper ends of the flanges 12. When both walls 15 are in place, the side walls 11 are locked together from any outward movement. Of course, the front and rear walls 15 are locked from any inward movement. Thus, the structure is securely braced from deformation. The portions 18 of the side walls extend downward and toward each other to form a hopper-shaped lower end to the upper portion of the receptacle, the edges of these portions 18 being so spaced from each other as to permit grain or other food in the upper portion of the receptacle being discharged in small amounts into the lower portion of the receptacle, but preventing the whole body of the grain from so descending.

The bottom 10 is provided immediately beneath the space 23 between the lower ends of the portions 18 with a perforation 24. A cover 25 is provided whose margins are inwardly bent, as at 26, to engage over the angularly turned flanges 20 and slide thereon, and this cover is provided at one end with a perforation 27 which, when the cover is in place, aligns with the perforation 24 so that a wire anchoring rod 28 may be inserted down through these perforations and driven into the ground, this wire rod thus holding the cover 25 in place against accidental removal and anchoring the container to the ground. I regard this as preferable, but it

is, of course, possible to drive a pin or other anchoring device down through the perforation 24 so that its head is below the upper end of the casing and then put on the cover.

5 In this case, the cover is not formed with the perforations 27 and 24.

It will be seen that my device is very effective for the purpose of holding grain or other feed, and that the material will feed downward from the hopper-shaped compartment in the upper end of the container gradually, and that these grains discharged onto the bottom of the container will be prevented from being scattered by the flanges 13, and 10 this grain will be protected by the outwardly projecting water sheds 19.

In actual practice, this container will be made from 7 to 8 inches high and 4 or 5 inches square, so as to contain a goodly 15 amount of grain. The opening 23 will only permit the grain to feed downward onto the tray or bottom of the container as it is taken away at the bottom. The separate parts from which the container is made may 20 have the marginal folds formed in them at the factory and be shipped in a flat or knocked-down condition, and then it is an easy matter to bend the side walls of the container up at right angles to the bottom 25 and connect the parts as heretofore described. Thus the device may be very compactly shipped.

While this device is adapted to be used for holding granular foods or material of 30 any kind and for any purpose, it is particularly designed as a holder for grain soaked with gopher poison, where it is particularly desirable that the poisoned grain shall be 35 protected from dust, rain, or from being blown away.

I claim:—

1. A container of the character described having a bottom and side walls, the front and rear margins of the side walls being 40 bent toward each other to form flanges, front and rear walls each consisting of two plates of metal, one of the plates having marginal flanges extending downward from its upper end a distance less than the length of the 45 plate and engageable with the flanges on the side wall and being angularly bent below these flanges, the other plate at its lower end being angularly bent in divergent relation to the first named angular bend, the 50 upper end of one of said plates being angularly flanged, said flange forming a stop limiting the downward movement of the front or rear plate with reference to the side walls, and a cover having sliding engagement 55 with said last named flanges.

2. A container of the character described having a bottom and side walls, the side margins of the side walls being bent toward each other to form flanges, the margins 60 of said flanges being inwardly and laterally

bent, front and rear walls each consisting of two plates of metal, one of the plates having marginal, inwardly turned flanges extending downward from its upper end a distance less than the length of the plate 70 and the plate being angularly bent below these flanges, the other plate having sliding engagement in said laterally bent flanges and at its lower end being angularly bent in divergent relation to the first named angular 75 bend, the side edges of the plate being notched to accommodate the flanges of the side walls, and the second named plate of the front wall being angularly flanged at its upper end, the flange forming a stop 80 limiting the downward movement of the front or rear plate with reference to the side walls, and a cover having inwardly extending marginal flanges slidably engaging the last named flanges. 85

3. A container of the character described comprising a bottom and side walls, the bottom wall having upwardly extending marginal flanges, the side walls having inwardly extending marginal flanges, the margins of 90 said flanges being bent laterally, front and rear walls having their margins bent to engage the rebent margins of said flanges and having flanges at their upper ends limiting the downward movement of the front and 95 rear walls, said front and rear walls being less in length than the side walls and formed to provide inwardly and downwardly extending convergent portions forming a hopper-shaped bottom for the upper portion of 100 the container and discharging material downward onto the bottom of the container, and a cover having sliding engagement with said upper flanges of the front and rear walls. 105

4. A container of the character described comprising a bottom and side walls, the bottom wall having upwardly extending marginal flanges, the side walls having inwardly extending marginal flanges, the margins of 110 said flanges being bent laterally, front and rear walls having their margins bent to slidably engage the rebent margins of said flanges and having flanges at their upper ends limiting the downward movement of the front and rear walls, said front and rear walls being less in length than the side walls and formed to provide inwardly and downwardly extending convergent portions and outwardly and downwardly divergent 115 portions constituting water sheds, and a cover having sliding engagement with said upper flanges of the front and rear walls. 120

5. A container of the character described having a bottom and side walls formed of 125 one piece of sheet metal, the side walls being bent upward at right angles to the bottom, the front and rear margins of the bottom being bent upward to form flanges, the front and rear margins of the side walls being 130

bent toward each other to form flanges, the margins of said flanges being inwardly and laterally bent, front and rear walls each consisting of two plates of metal, one of the 5 plates having marginal, inwardly turned flanges extending downward from its upper end a distance less than the length of the plate and being angularly bent below these flanges, the upper plate having sliding engagement in said laterally bent flanges and 10 at its lower end being angularly bent in divergent relation to the first named angular bend, the side edges of the plate being notched to accommodate the flanges of the

side walls, and said second named plate of 15 the front wall being angularly flanged, said flange forming a stop limiting the downward movement of the front or rear plate with reference to the side walls, and a cover having inwardly extending marginal flanges 20 slidingly engaging the last named flanges.

In testimony whereof I hereunto affix my signature in the presence of two witnesses.

EINAR A. TANNAS.
